ASPIRATING NOZZLE ASSEMBLY

Eugene C. Briggs, Dayton, Ohio, assignor to Master Consolidated, Inc., Dayton, Ohio, a corporation of Ohio

Filed Feb. 11, 1965, Ser. No. 431,862

6 Claims. (Cl. 239—406)

This invention relates to improvements in siphon type nozzles and more particularly to simplifying such nozzle structures and rendering them adaptable to a wider variety of applications. Embodiments feature low cost assembly. They are uniquely designed to facilitate an interchange of orifice tubes offering different flow rates, the advantages of which are believed obvious.

A primary object of the invention is to provide a siphon type nozzle unit which is more economical to fabricate, more efficient and satisfactory in use, adaptable to a wider variety of applications and unlikely to malfunction.

Another object of the invention is to simplify the assembly and disassembly of aspirating type nozzle units so as to render them more versatile in application.

A further object of the invention is to provide a siphon type nozzle unit with a more readily replaceable orifice tube.

An additional object of the invention is to provide a novel siphon type nozzle unit wherein a change in flow rate may be simply and quickly achieved.

Another object of the invention is to provide a siphon type nozzle unit possessing the advantageous structural features, the inherent meritorious characteristics and the means and mode of use herein described.

With the above and other incidental objects in view as will more fully appear in the specification, the invention intended to be protected by Letters Patent consists of the features of construction, the parts and combinations thereof, and the mode of operation as hereinafter described or illustrated in the accompanying drawings, or their equivalents.

Referring to the accompanying drawing wherein is shown one but obviously not necessarily the only form of embodiment of the invention,

FIG. 1 is a longitudinal section of a nozzle unit in accordance with the invention;

FIG. 2 is a detail of the nozzle stem, shown partly in section;

FIG. 3 is an end view of the stem; and

FIG. 4 is a view of the complete nozzle unit.

Like parts are indicated by similar characters of reference throughout the several views.

The nozzle unit illustrated features extreme simplicity of construction. It consists of a stem 10, cap 11 and an orifice tube 12.

The stem 10 is a tubular body featuring a central bore 13 of uniform diameter from its entrance end 14 to a plane adjacent and spaced from its discharge end 15. From this plane the bore 13 is conically reduced for a short section 16 which is followed by a short uniformly cylindrical orifice section 17 terminating in a conically expanded lip 18.

The exterior of the body providing the stem 10 features a uniform diameter from its entrance end to a shoulder 19 defined by a cylindrically expanded section 20 at its approximate center. The section 20 is followed by a conically tapered section 21 convergent to a short cylindrical section 22. The section 22 terminates in a shoulder 23 defined by a flange portion 24. The flange portion 24 is followed by a cylindrically expanded stem portion 25 featuring an undercut 26 at its juncture with the flange and terminating at its end remote from the flange in a shoulder 25'. The relative diameters of the stem portion 25 and flange 24 are such to define a narrow annular abutment

2

surface 27 on the face of the flange most adjacent and peripheral to the stem portion 25. The end of portion 25 terminates in a chamfer in spaced relation to the discharge end of the stem. The outer diameter of the stem beyond the portion 25 is generally equal to that of the stem at its entrance end except at its discharge extremity which features a conically convergent taper 28.

As will be readily apparent from the drawings the flange 24 defines the largest radial projection on the stem 10.

The cap 11 has a cup shape, its inner surface forming a cylindrical wall section 29 having one diameter adjacent its head 30 and a relatively larger diameter adjacent its open end. Its head 30 is dished to a central aperture 31 arranged coaxial with the open end of the cap.

The outer surface of the cap wall is threaded from its open end, coextensively with the diametrically enlarged portion of its inner surface. This threaded portion is followed by a projected flange 32 beyond which the head of the cap has a conically convergent form.

In assembling the cap 11 to the stem 10, the stem portion 25 is press fit to nest within the diametrically enlarged open end of the cap, in the process of which the open end of the cap wall achieves a sealing abutment with the annular surface 27 on the stem flange 24. This positions the discharge portion of the stem 10 interiorly of and in concentric spaced relation to the cap wall 29. The discharge extremity of the stem positions in axially spaced relation to the cap aperture 31 and the orifice 17 aligns coaxial therewith. The limitation of the cap by abutment of the peripheral wall thereof with the stem surface 27 insures the formation of a chamber 35 about the nested discharge end of the stem.

As seen in FIG. 1 of the drawings, the orifice tube 12 is press fit at one end in the orifice 17 of the stem 10 while its other end positions within the aperture 31 of the cap 11 as the cap is applied to the stem. In the example illustrated the discharge end of the tube 12 falls just short of the outermost surface 33 of the head end of the cap.

The stem 10 has four equidistantly spaced skewed passages 34 angled at 30° to the stem axis, opening at one end from the shoulder 23 of flange 24 and at their opposite ends from the shoulder 25' to the interior of the chamber 35.

It is a unique feature of the nozzle unit above described that one may have a number of orifice tubes 12 having different size bores, each of which may be similarly press fit in the orifice 17 of the stem 10. The tubes may be easily interchanged to achieve a desired flow rate with the same basic cap and stem.

The described nozzle unit may be readily applied in a conventional burner unit, the entrance end of the stem 10 being coupled to a fuel line and the entrance ends of the passages 34 exposed to a pressured flow of air.

The passages 34 are operable to produce an optimum channelling of air to swirl into the chamber 35 and about the discharge end of the stem. This swirling flow of air exits at a high velocity through the limited passage between the discharge end of the orifice tube 12 and the wall of the aperture 31 in the cap 11. The tube is thereby exposed to a highly developed suction which draws fuel therethrough from the fuel source. The swirl characteristics are such to thoroughly atomize the fuel as it exits from the tube.

Thus, the invention structure is not only simple but highly effective in use. It features a ready interchangeability of its orifice tube which by a proper selection of its flow passage may obviously achieve any desired result. From the above description it will be apparent that there is thus provided a device of the character described possessing the particular features of advantage before enumerated as desirable, but which obviously is suscep-

70

tile of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise but one of several modes of putting the invention into effect, and the invention is therefore claimed in any of its forms or modifications within the legitimate and valid scope of the appended claims.

Having thus described my invention, I claim:

1. An aspirating nozzle for a fuel burning space heater or the like consisting per se of a tubular stem, a selective control tube and a cap, said stem having its one end adapted for coupling to a fuel flow line, said selective control tube having a releasable slip fit to and forming an extension of the other end of said tubular stem, said stem having an integrally formed radially projected flange means on a section of its exterior wall, said cap mounting in an enclosing spaced relation to said other end of said stem and the slip fit control tube to have its open end seat in a sealed abutting relation to said flange means, said cap forming a flow chamber thereby, passages in said flange means for delivering a pressured flow of air to and through said chamber, said cap having an aperture coaxial with the discharge end of said control tube and the control tube defining with the portion of said cap forming said aperture a restricted flow path for high velocity movement of air from said chamber to aspirate fuel through said stem and said control tube, the slip fit of said control tube facilitating a quick interchange thereof to suit the application of said nozzle.

2. A nozzle as in claim 1 characterized by said control tube being a flow restricting device the projected extremity of which terminates within the aperture in said cap.

3. A nozzle as set forth in claim 1 characterized by said flange means being stepped to have a relatively reduced portion fit to plug the open end of said cap while the remainder serves as a limiting abutment for said cap.

4. An aspirating nozzle for a fuel burning space heater or the like, including a tubular stem having a through longitudinal bore therein for flow of a fluid fuel through said stem, said stem having inlet and discharge ends with respect to the direction of fluid flow, a cup shaped cap receiving the discharge end of said stem through its open end, the closed end of said cap providing an aperture aligned with the bore in said stem, flange means occupying an intermediate position on the exterior of said stem and including a portion to which the open end of said cap seats to limit relative approaching motion of said stem and cap and further including another portion received in said cap to space the discharge end of said stem radially from said cap, the first said portion being positioned to space the inner extremity of said discharge end of said stem longitudinally from the closed end of said cap, said flange means defining in said cap a chamber enclosing the discharge end of said stem, flow passage means for introducing air under pressure into said chamber to escape through the aperture in the closed end of said cap, and an orifice tube interchangeably installed in the discharge end of said stem as an extension of the bore therein and bridging said chamber to extend at least into said aperture in the closed end of said cap, said aperture exceeding in diameter the outside diameter of said tube.

5. An aspirating nozzle according to claim 4, characterized in that said flow passage means comprises openings formed angularly in said flange means to produce a swirling flow of air in said chamber.

6. An aspirating nozzle according to claim 4, characterized in that said tube projects axially a substantial distance from said stem facilitating its manipulation for withdrawal from and replacement in said stem.
